CLOYD M. CHAPMAN, OF DOUGLASTON, NEW YORK, ASSIGNOR TO C. J. TAGLIABUE
MANUFACTURING COMPANY, A CORPORATION OF NEW YORK.

BURNER FOR CLOSED OIL-TESTERS.

1,275,223.

Specification of Letters Patent.

Patented Aug. 13, 1918.

Application filed March 13, 1916. Serial No. 83,757.

To all whom it may concern:

Be it known that I, CLOYD M. CHAPMAN, a citizen of the United States, and a resident of Douglaston, Queens county, New York, have invented certain new and useful Improvements in Burners for Closed Oil-Testers, of which the following is a specification.

My invention relates to an improved type of burner adapted to be operated either with oil or gas in connection with closed oil testers of the type wherein a burner tip is arranged to be lowered into an opening in the cover of a cup containing oil to be tested simultaneously with the removal of the lid from said opening, the burner being raised from said position in correspondence and simultaneously with the closing of the lid.

More particularly my invention relates to an improved burner of the character described as applied to and used with an improved form of closed oil tester which constitutes the subject matter of a patent application filed by Charles J. Tagliabue, August 14, 1915, Serial No. 45,466.

In the patent application just referred to, a closed oil tester is shown which comprises an oil containing cup having a cover part of which is slidable and is engaged with an element attached to a rotatable gas pipe provided with a burner tip which enters the opening in the oil cup cover as the slide which normally closes said opening is withdrawn by the rotation of the pipe. The burner of this particular tester is adapted to burn gas only, and hence, while convenient as a laboratory instrument, is not adapted to conditions where gas is not obtainable. In practice it is often necessary to make flash tests in the oil fields or in refining works where there is no gas supply, but of course ample oil supply. In the prior art it has been usual to supply this need by providing both an oil burner and a gas burner and arranging the tester so that the one burner could readily be exchanged for the other. With my invention, now to be described, the same burner with practically no change may be used with either gas or oil at will and with equally good results.

My invention will be better understood by referring to the accompanying drawings which illustrate, in connection with my improvement, so much of the Tagliabue invention above referred to as is necessary to an understanding of the invention. Of these

drawings, Figure 1 is a central sectional elevation taken along the line 1—1 of Fig. 2; Fig. 2 is a top plan view; and Fig. 3 is a central section along the line 3—3 of Fig. 2.

In the drawings the oil cup 1 is immersed in a water bath 2 (the heating means employed is not shown). A cover 3 is provided for the oil cup and has a central opening 4 and peripheral vent openings 5 and 6. A slide 7' is provided with two openings corresponding to openings 4 and 5 and of such length that when moved sufficiently to the rear (to the left, Fig. 3) the three openings 4, 5 and 6 will be uncovered.

Thermometers 7, 8 are disposed so as to give the temperature of the oil being tested and of the water respectively.

Erected upon the cover 3 is a pair of posts 9 which serve as bearings for the burner 10. This burner comprises a box 11 having a removable plug cover 12, by means of which the box may be filled with oil, and a nozzle or burner tip 13 inserted in its front near the bottom.

Pipe sections 14 and 15 open into and are fixed to box 11 on each side and pass through supports 9, serving therefore as journals. Pipe 15 is extended beyond post 9 and provided with a knurled head 16 and with a spring 17, one end of which is attached to the pipe and the other to the adjacent post.

The spring 17 is so wound that the burner tip 13 is normally inclined upwardly as shown in Fig. 1 and (dotted) in Fig. 3.

The slide is provided with a pair of upwardly projecting pins 18 arranged to be engaged by a U-shaped member 19, which projects radially between them from pipe 15.

Pipe 14 terminates in a nipple 20 over which may be slipped the usual rubber tube 14' for the supply of gas and a cock 21 controls the opening through pipe 14.

In making a test the knurled head 16 is rotated between thumb and finger, thus causing the box 11 to be turned, against the resistance of spring 17, so as to throw burner tip 13 downwardly and into the central opening 4, which opening the slide 7' simultaneously uncovers by reason of the pins 18 and member 19.

Preferably a small amount of cotton or the like is placed in the box 11 and the burner tip 13 is provided with a suitable wick 22 which reaches back into the cotton.

If the improved tester is to be used with oil the plug 12 of box 11 is removed, a suitable quantity of oil is placed in the box and the plug replaced; the burner tip may then 5 be lighted. The rubber tube 14' should be withdrawn from the nipple 20 and the cock 21 should be opened somewhat in order to supply a suitable amount of air to the interior of the box, so as to tend to maintain 10 the same air pressure within and without the receptacle, thereby facilitating the supply of oil to the wick.

The cotton will have absorbed the oil and hence there will be practically no tendency 15 for the oil to run out of the box by way of pipe 14 or by way of the burner tip when the latter is inclined downwardly.

If gas is to be used instead of oil the cock 21 should be suitably opened and the 20 rubber tube 14' attached to the nipple 20. The wick and cotton may be removed from the burner box if desired, although this is not essential.

Having described my invention I claim:

25 1. An oil tester comprising an oil cup for the oil to be tested, said cup having an opening in the top thereof, a closed receptacle hav-

ing a burner tip opening therefrom, said receptacle being pivotally supported above the 30 cup so as to permit the burner tip to be lowered into the receptacle opening, cotton saturated with oil within said receptacle, a wick in said burner tip, a pipe opening 35 into said receptacle and adapted for the flow of either gas or air, and a valve in said pipe.

2. An oil tester comprising an oil cup for the oil to be tested, said cup having an opening in the top thereof, a closed receptacle having a burner tip opening therefrom, said 40 receptacle being pivotally supported above the cup so as to permit the burner tip to be lowered into the receptacle opening, cotton saturated with oil within said receptacle, a wick in said burner tip, one of the pivotal 45 supports being hollow and adapted to the flow of either gas or air, and a valve for opening or closing the passage through said pivotal support.

In testimony whereof I have hereunto set 50 my hand.

CLOYD M. CHAPMAN.
